(57) **CLAIM**

The ornamental design for ceramic heater, as shown and described.

DESCRIPTION

FIG. 1 is a perspective view of the design.

FIG. 2 is a front view of the design.

FIG. 3 is a rear view of the design.

FIG. 4 is a left view of the design.

FIG. 5 is a right view of the design.

FIG. 6 is a top view of the design; and,

FIG. 7 is a bottom view of the design.

The broken lines depict portions of the ceramic heater and form no part of the claim.

1 Claim, 5 Drawing Sheets(56)
